(57) **CLAIM**

What is claimed is the ornamental design for a digital vibration meter, as shown and described.

DESCRIPTION

FIG. 1 is a perspective view of a digital vibration meter according to the new design;

FIG. 2 is a front view of the digital vibration meter shown in FIG. 1, the rear view being identical thereto;

FIG. 3 is a top view of the digital vibration meter shown in FIG. 1;

FIG. 4 is a side elevation view of one side of the digital vibration meter shown in FIG. 1, the other side view being identical thereto;

FIG. 5 is a bottom view of the digital vibration meter shown in FIG. 1;

FIG. 6 is a perspective view of another embodiment of a digital vibration meter according to the new design;

FIG. 7 is a front view of the digital vibration meter shown in FIG. 6, the rear view being identical thereto;

FIG. 8 is a top view of the digital vibration meter shown in FIG. 6;

FIG. 9 is a side elevation view of one side of the digital vibration meter shown in FIG. 6, the other side view being identical thereto; and,

FIG. 10 is a bottom view of the digital vibration meter shown in FIG. 6.

Features shown in broken lines form no part of the claimed design.
